UNITED STATES PATENT OFFICE.

FRANK R. BATCHELDER, OF WORCESTER, MASSACHUSETTS.

CARTRIDGE-CARRIER.

1,175,584.

Specification of Letters Patent.

Patented Mar. 14, 1916.

Application filed April 14, 1915. Serial No. 21,438.

To all whom it may concern:

Be it known that I, FRANK ROE BATCHELDER, a citizen of the United States, residing at Worcester, in the county of Worcester, State of Massachusetts, have invented a certain new and useful Improvement in Cartridge-Carriers, of which the following is a specification, reference being had therein to the accompanying drawings.

10 The invention relates to cartridge-carriers having pockets for receiving groups or series of cartridges held together by clips, or otherwise. It is common to make the pockets of a size permitting two or more groups or series to be placed within a single pocket. Sometimes the pockets are constructed with partitions by which the interior of a pocket is divided into two or more compartments, each adapted to receive a group or series of 15 cartridges.

20 The invention comprises improvements in cartridge-carriers having pockets of this type.

25 A general object of the invention is to enable the dimensions and size of a pocket, and the extent to which it stands out or projects from its supporting backing, to be reduced without lessening the containing capacity of the pocket.

30 The invention consists, mainly, in a cartridge-carrier having a cartridge-containing pocket furnished with one or more diagonal or oblique partitions separating the interior space between the front and back walls 35 thereof into tapering compartments, with the taper of one compartment reversed relatively to that of the next. A pocket thus constructed is adapted to receive within each tapering compartment a group or series of cartridges having the length thereof extending in the direction of the length of the mouth of the pocket, and with the clip of such group or series occupying the wide end of the compartment and the points of 40 the bullets occupying the narrow end of the compartment. The group or series of cartridges that occupies the adjoining compartment will be disposed reversely relative to the group or series first referred to, so that 45

50 the clip of the second group or series of cartridges will be alongside the points of the bullets of the first group or series, and vice versa.

55 The invention is applicable equally in the case of a pocket having a single partition dividing its interior space into two compart-

ments, and in the case of a pocket having two or more partitions dividing its interior space into three or more compartments. In the latter cases the partitions incline oppositely alternately, and likewise the compartments taper in opposite directions, alternately.

60 Another object of the invention is to enable a group or series of cartridges, occupying a position in which their lengths correspond in direction with that of the mouth of the pocket, to be withdrawn bodily from the pocket without the cartridge that is exposed at the mouth becoming disconnected from the clip as a result of being grasped and pulled upon to effect the withdrawal, and without the innermost cartridges being 65 left behind in the pocket. This object is attained by means of a withdrawing strap 70 with which the side of the first cartridge to enter the pocket becomes engaged as it enters. By pulling upon the outer end of the strap the entire group or series is moved 75 part way out of the pocket.

80 Another object of the invention is to prevent a group or series of cartridges, occupying a pocket with their lengths extending in the direction just mentioned from assuming a canted position which would cause 85 the points of the bullets of the cartridges that are nearest the mouth to rub against and catch and dig into the adjacent end of the pocket so as to impede the withdrawal of the cartridges and injure the pocket. 90 This object is attained by means of a rest for the small end of the innermost cartridge whereby the canting of the group or series is prevented and the latter is given a position in which the line containing their points 95 is nearly parallel with the said adjacent end of the pocket. This facilitates the movement of the group or series of cartridges straight outward from the interior of the pocket.

100 The drawings show illustrative embodiments of the features of the invention.

In the drawings,—Figure 1 is an isometric view of a portion of a cartridge-carrier comprising one pocket and its flap or cover, with 105 the said pocket divided into two oppositely tapering compartments by means of a single oblique partition. Fig. 2 is a front elevation of the same. Fig. 3 is a plan view thereof with the flap or cover in horizontal 110 section, the upper portion thereof being removed. Fig. 4 is a view in vertical section

in the plane indicated by the dotted line 4—4, Fig. 3. Fig. 5 is a similar sectional view, but showing a modification in the support for the bullet-ends of the cartridges. Fig. 6 is an isometric view of a portion of a cartridge-carrier comprising two pockets, each of the latter having the interior space thereof separated by means of two partitions into three compartments. Fig. 7 is a diagrammatic plan of one of the pockets of Fig. 6, with the flap or cover in section above the mouth of the pocket, and with the partitions and the cartridges and clips within the respective compartments of the pocket spaced widely apart in order to show clearly the arrangements and relations of the said partitions and the cartridges, and the taper of the compartments.

Having reference to the drawings and first to Figs. 1 to 4,—a portion of the supporting-band of a cartridge-carrier is shown at 1, and 2 is a pocket thereon, its cover being represented at 3. Fastenings of usual character for keeping the cover in closed condition are shown at 4, 4^a. The said cartridge-carrier is composed of woven material, or in other words it is a so-called woven cartridge-carrier, and the pocket 2, with its partitions, is formed upon the band 1 in the weaving process and thereby made integral therewith. A portion of the band 1 serves as the back-wall 1^a of the pocket. The end-walls 2^a, 2^b, of the pocket spring forward from the said back-wall. The front wall 2^b extends from one end wall to the other, and the backing end-walls, and front wall are connected together by the bellows-like bottom 2^c, Fig. 4, of the pocket.

The partition of the pocket is marked 5. The obliquity or inclination of the said partition is shown clearly in Figs. 1 and 3, as is also the taper of the respective compartments, and the fact that the latter taper in opposite directions. The taper of each compartment corresponds substantially with that of the group or series of cartridges 6, 6, etc., received therein, namely from the clip 6^a of such group or series to the points of the bullets 6^b, 6^b, etc. Each group or series of cartridges fits snugly and tightly within its compartment, without the straining of the partitions and walls heretofore customary, and without the excess of material in the partitions which sometimes has been found necessary. The groups or series of cartridges occupying the different compartments have their clips respectively disposed at the opposite ends of the respective compartments, so that the clip of one group or series is alongside the points of the bullets of the adjacent group or series, and vice versa. The different groups or series fit closely together side by side, and require for their joint reception a minimum of space, consequently enabling the dimensions

of the pocket to be kept small, and so that the extent to which the pocket stands out or projects from the band 1 may be reduced.

Figs. 6 and 7 show pockets which are each divided by means of two partitions into three compartments. The said compartments taper in opposite directions alternately, so that the clips of the first and third groups of cartridges are located at one end of a pocket and that of the second group is located at the other end. In practice the dimensions of the pockets will be proportioned to correspond more closely to those of the cartridges and clips than in Figs. 6 and 7, so that the various parts of the pockets will fit snugly against the cartridges and hold them frictionally.

Withdrawing straps are shown at 7, 7^a, Figs. 1 to 5, for moving the respective groups or series of cartridges partly out from the different compartments, so as to facilitate the removal of a group or series from the pocket. The strap 7, as shown in Figs. 4 and 5, has one end thereof made fast to the rear side of the partition 5 at an intermediate distance from the open mouth of the rear compartment. The attachment is effected preferably by means of stitches 7^b.

In inserting a group or series of cartridges within the rear compartment, the leading cartridge carries the strap 7 in a bend or loop to the bottom of the compartment, the strap extending from its point of attachment 7^b downward at the front of the cartridges, partly around the said leading cartridge, then up at the rear of the group or series of cartridges and between the same and the back wall 1^a of the pocket and then across the tops of both compartments. The free extremity of the said strap is made fast by being bent down in front of the pocket and engaged with a stud 7^c projecting from the front wall 2^b. An eyelet 7^d is provided in connection with the downturned portion of the said extremity of the strap 7. The strap 7^a is applied and arranged in connection with the front compartment very much the same as in the case of the strap 7 in the rear compartment. One end of strap 7^a is attached, as at 7^b, Fig. 5, to the inner surface of the front wall 2^b, so that when a group of cartridges is inserted into the front compartment the leading cartridge of such group carries the strap 7^a down to the bottom of the compartment, and the strap consequently extends from its point of attachment to the front wall 2^b down around the leading cartridge, then up between the group of cartridges and the partition 5, then across the top of the front compartment and then down in front of the front wall 2^b under the strap 7, and is engaged by its eyeleted extremity with the stud 7^c projecting from the said front wall 2^b. The withdrawing straps serve to prevent the cartridges from falling

or being thrown out of the pocket when the cover or flap 3 is unfastened. When it is desired to withdraw the cartridges from the rear compartment the free extremity of the strap 7 is disengaged from the stud 7^c, and then by pulling upward upon the said strap the group of cartridges within the said compartment will be lifted partly out of the latter so that they may be grasped and readily 10 be withdrawn completely. When the withdrawal of the cartridges from the front compartment is desired, the same operations are repeated with the strap 7^a after the strap 7 has been disengaged from the holding stud 7^c. The withdrawing straps are omitted 15 from the pockets of Figs. 6 and 7 but may be employed in connection with such pockets in practice, if desired.

Two arrangements are shown for keeping 20 the group or series of cartridges that is contained within a compartment from assuming an endwise canted position. Figs. 2 and 4 show a rest-block 9, preferably composed of felt, located at the bottom of a pocket in 25 position to engage with the portion of reduced diameter at the bullet-end of the innermost cartridge. This rest supports the small end of the innermost cartridge in such 30 position that a line touching the points of the group or series of cartridges will be approximately parallel with the adjacent end-wall of the pocket. In the absence of the rest, the innermost cartridge would approach the bottom of the pocket at its small 35 end, with the result that the group of cartridges would become canted endwise so as to cause the points of the bullets of the outermost cartridges to bear against the adjacent end-wall of the pocket and either dig 40 into such end-wall or catch against the same so as to impede the withdrawal of the cartridges from the pocket and cause injury to the end-wall. In some cases the separate rest-block or filler-block 9 may be dispensed 45 with, and a rest for the small end of the innermost cartridge be provided by binding together the sides of the pocket-compartment as at 9^a in Fig. 5. The sides may thus be bound together either by the process of 50 weaving or by stitches applied after the weaving.

The improvements comprised in the pres-

ent invention are not restricted to application to pockets having their mouth openings at the top thereof. I contemplate their employment in connection with pockets having mouth-openings located laterally thereof. 55

I claim as my invention:—

1. A woven cartridge-carrier having a cartridge-containing pocket furnished with 60 one or more partitions crossing the mouth or opening of the pocket diagonally or obliquely and dividing the interior space thereof into tapering cartridge-receiving compartments, with the taper of one compartment reversed relatively to that of the 65 next.

2. A woven cartridge-carrier having a cartridge-containing pocket woven with one, or more integral partitions crossing the 70 mouth or opening of the pocket diagonally or obliquely and dividing the interior space thereof into tapering cartridge-receiving compartments, with the taper of one compartment reversed relatively to that of the 75 next.

3. A woven cartridge-carrier having a cartridge-containing pocket adapted to contain a group or series of cartridges with the 80 length of the latter corresponding in direction with that of the mouth of the pocket, and also having a rest for the small end of the innermost cartridge compensating for the reduced diameter of such portion and preventing endwise canting of the said 85 group or series toward the adjacent end-wall of the pocket.

4. A woven cartridge-carrier having a cartridge containing pocket adapted to contain a group or series of cartridges with the 90 length of the latter corresponding in direction with that of the mouth of the pocket, and also having an inserted rest-block for the small end of the innermost cartridge compensating for the reduced diameter of 95 such portion and preventing endwise canting of the said group or series toward the adjacent end-wall of the pocket.

In testimony whereof I affix my signature in presence of two witnesses.

FRANK R. BATCHELDER.
